(57) **CLAIM**

The ornamental design for an accent lighting fixture as shown and described.

DESCRIPTION

FIG. 1 is a top back perspective view of the claimed design; FIG. 2 is an alternative perspective view of the claimed design;

FIG. 3 is a top plan view of FIG. 1;

FIG. 4 is a bottom plan view of FIG. 1.

FIG. 5 is a left side elevation of FIG. 1;

FIG. 6 is a right side elevation of FIG. 1.

FIG. 7 is a front elevation view of FIG. 1; and,

FIG. 8 is a back elevation view of FIG. 1.

The broken lines shown in the drawings illustrating unclaimed portions of the accent lighting fixture form no part of the claimed design.
